(57) **CLAIM**

The ornamental design for a wall block, as shown and described.

DESCRIPTION

FIG. 1 is a perspective view of a wall block, as viewed from the front, top, and one side of the block.

FIG. 2 is another perspective view of the wall block of FIG. 1, as viewed from the rear, top, and one side of the block.

FIG. 3 is a top plan view of the wall block of FIG. 1.

FIG. 4 is a bottom plan view of the wall block of FIG. 1.

FIG. 5 is a left side elevation view of the wall block of FIG. 1.

FIG. 6 is a right side elevation view of the wall block of FIG. 1.

FIG. 7 is a front elevation view of the wall block of FIG. 1; and,

FIG. 8 is a rear elevation view of the wall block of FIG. 1. The broken lines in the drawings represent features of the wall block that form no part of the claimed design.

1 Claim, 5 Drawing Sheets
